UNITED STATES PATENT OFFICE.

WALTER L. MARR, OF FLINT, MICHIGAN.

EXPLOSIVE-ENGINE.

1,259,891.

Specification of Letters Patent. Patented Mar. 19, 1918.

Application filed September 19, 1914. Serial No. 862,454.

To all whom it may concern:

Be it known that I, WALTER L. MARR, a citizen of the United States of America, residing at Flint, in the county of Genesee and State of Michigan, have invented certain new and useful Improvements in Explosive-Engines, of which the following is a specification, reference being had therein to the accompanying drawings.

10 This invention relates to explosive engines and to an arrangement of the valves thereof whereby positive opening and closing of the ports in proper timed relation to the piston movement is obtained and whereby the valves

15 are not only maintained in such cool condition as to be readily lubricated but also are arranged to minimize leakage under high compression. A further feature of the invention is the noiseless action of the valves

20 which are of the slide type.

The invention consists in the matters hereinafter set forth and more particularly pointed out in the appended claims.

In the drawings,

25 Figure 1 is a view, partially in longitudinal section and partially in elevation, largely diagrammatic, of the upper portion of an engine cylinder that embodies features of the invention;

30 Fig. 2 is a view in transverse section taken on or about the line II—II of Fig. 1;

Fig. 3 is a view in transverse section taken on or about line III—III of Fig. 1; and

35 Fig. 4 is a plan view, reduced in scale showing one form of arrangement of the valve operating mechanism with minor details omitted.

Referring to the drawings, the wall 1, of an open-ended engine cylinder, that is herein shown with provision for water jacketing, 40 encircles a piston 2 of conventional type that reciprocates adjacent to ports near or at the explosion end of the cylinder. As herein shown, these ports may be two in 45 number, and oppositely disposed, one of them 3 forming the intake and the other 4, the exhaust. The ports are properly proportioned and designed to facilitate the proper ingress and egress of fresh charges 50 and exhausted gases.

An annular casing 5, extends from the explosive end of the cylinder in axial alinement therewith and is closed by a cap 6 that is preferably detachable. Longitudinal guide 55 channels 7 are formed in the outer face of

the casing 5 in vertical alinement severally with the ports 3 and 4 the lower portions of the channels opening through the casing wall. Valve rods 8 and 9 in longitudinal sliding engagement in these channels, have 60 lateral end portions 10 and 11 or studs that extend through the lower open portions of the guide slots and engage in bosses 12 and 13 of segmental valve sleeves 14 and 15. Removable inserts or plates 28 retain the valve 65 rods 8 and 9 in operative position and permit free access for inspection, repair or assembling, and may aid also in maintaining the casing 5 and cap 6 in position. Or other suitable operative connection may be made 70 between the members 8 and 9 and the segments 14 and 15 whereby reciprocation of the members 8 and 9 produces corresponding movement of the segments, which have longitudinal sliding engagement with the inner 75 periphery of the casing 5. A cylinder head 16 concentric with the casing 6 acts as a spacer guide between the segments 14 and 15 beyond the cylinder ports, the bearing bosses 80 12 and 13 plying in outer longitudinal recesses formed in the head or preferably in ribs 17 thereof. A pair of packing rings 18 on opposite sides of the open end portions of the guide channels 7 or other suitable means between the head 16 and the segments 85 14 and 15 minimize any tendency to leakage around the latter. The head may or may not be integral with the cap, and is preferably chambered for water-cooling or jacketing.

90 A cam shaft 19 that is arranged to be operated in timed relation to the movement of the piston 2, is appropriately mounted on the casing 5 or cap 6 and is provided with a pair of cams 20 and 21. A rock arm 95 22 is pivoted at one end to a stud 23 on the cap to oscillate over the cam 20 on which it rides, the other end being loosely articulated as by a pin and slot connection indicated at 24 to the link or slide rods 9. The 100 other cam 21 which is in opposite relation to the cam 20, oscillates a rock arm 25 pivotally attached at one end to a stud 26 of the cap 6 and loosely articulates at the other as indicated at 29 to the link or slide 105 rods 9. The arm may have spring-pressed relation with the cam as herein diagrammatically indicated, or positive connection therewith. The parts are so proportioned and disposed that under the op- 110

eration of the cams the segments alternately open and cut off the ports 3 and 4 respectively, the driving mechanism for the cam shaft being of course such as will give it 5 the proper timed relation to the piston movement.

As a result of this construction, the engine valve mechanism is positive in action, is readily assembled, presents minimum opportunity for leakage and insures proper closing and opening of the ports. Inasmuch as the cams may be made to operate as quickly as desired the ports may be uncovered or closed with such rapidity as to provide for 10 high piston speed. The major portions of the segmental sleeves are not exposed to the high temperature of the combustion end of the cylinder and therefore are not liable to stick or jam in the annular ways in which 15 they oscillate. As the area then exposed is very slight in comparison with the portions of the segments which slide in the annular guiding space formed by the head and casing entirely beyond the explosion space of 20 the cylinder, lubrication is readily effected and undue wear and tendency to stick or bind, difficulties common to slide-valves in explosive engines, are prevented. The mechanism for operating the valve segments 25 may be of any preferred type consistent with good mechanical design.

Obviously, changes in the details of construction may be made without departing from the spirit of my invention and I do 30 not care to limit myself to any particular form or arrangement of parts.

What I claim is:—

1. In an explosive engine, a cylinder having ports near the open exhaust end, a casing 40 mounted on the explosion end in axial alignment with the cylinder, a head mounted in the casing and arranged to form therewith an annular guideway, a segmental valve reciprocable longitudinally in the 45 guideway, a rotatable cam mounted on the head, and oppositely disposed oscillatory arms pivoted on the head in operative relation to the cams and coupled to the sleeve

to open and close the ports in timed relation to the engine cycle.

50

2. In an explosive engine, a cylinder having ports near one end, a casing on said end in axial alignment with the cylinder, a head in the casing coöperating therewith to form an annular valve guideway in axial 55 alignment with the cylinder, a segmental valve reciprocable in the guideway in alignment severally with the cylinder ports, members reciprocable longitudinally of the casing parallel to the segments to which they 60 are severally coupled, a cam shaft and cams mounted on the head and rock arm pivoted on the casing head and operated by the cams to shift the reciprocable members to which they are respectively pivoted, the 65 segments and coöperating mechanism forming a unit bodily removable from the cylinder.

3. In an explosive engine, a cylinder ported near the open explosion end, a casing 70 aligned with the cylinder on the open end thereof, a cap mounted on the casing, an annular head depending into the casing and forming with the latter an annular guide space aligned axially with the cylinder bore, 75 slide valve members reciprocable longitudinally of the casing in this guide space, a valve rod for each guide member reciprocable in an exterior longitudinal channel of the casing, a lateral extension on each 80 rod extending through an opening into the guide space from the channel and engaging into a recess in the adjacent valve member, a rock arm for each segment oscillating on the cylinder cap articulated to the valve 85 rod, a cam shaft journaled on the casing transversely to the rock arms and provided with cams for lifting the latter, and spring members for maintaining operative relation between the cam shaft and rock arms. 90

In testimony whereof I affix my signature in presence of two witnesses.

WALTER L. MARR.
